UNITED STATES PATENT OFFICE.

FARRON S. BETTS, OF NEW YORK, N. Y., ASSIGNOR TO VICTOR TALKING MACHINE COMPANY, A CORPORATION OF NEW JERSEY.

ALBUM FOR HOLDING TALKING-MACHINE RECORDS.

1,287,842.

Specification of Letters Patent.

Patented Dec. 17, 1918.

Application filed November 6, 1915. Serial No. 59,929.

To all whom it may concern:

Be it known that I, FARRON S. BETTS, a citizen of the United States, and a resident of the city of New York, in the county of New York and State of New York, have invented certain new and useful Improvements in Albums for Holding Talking-Machine Records, of which the following is a specification.

10 The objects of my invention are to provide an album neat and attractive in appearance in which talking machine records can be conveniently stored; in which the record containing or holding units are snugly and 15 securely held, but from which said units may be easily removed and replaced; in which the envelop or record container is provided with a stiffened portion coöoperating with a rigid back or side to which the record holding units are secured so as to prevent the 20 liability of tearing or breaking the envelop; and to prevent the records when placed in the envelops or containers from slipping in the envelop to a position near the edge of the 25 album to which the envelops are attached, in which position the records would be liable to become broken in opening the album, and in which position the records have a tendency to separate the envelop or container 30 from the back and to unduly wear the envelop or container.

Other objects of my invention will appear in the specification and claims below.

In the drawings forming a part of this application in which the same reference characters are employed to designate the same parts throughout the various views, Figure 1 is a perspective view of my improved album with all but one record containing unit removed showing the construction of the album; the manner in which the record containing units are secured to the back, and indicating in dotted lines and in a partial sectional view of the corner of one 45 envelop the manner in which each envelop or record container is folded; and

Fig. 2 is a sectional view of a portion of the album through the back of the album on a plane parallel with the top and bottom 50 edges of the cover.

The album consists of a back 1 provided with a series of longitudinal grooves 2 extending the length of the inner side of said

back, said back being preferably slightly curved in transverse cross-section as clearly indicated in the drawings. The back is preferably made of wood, although, if desired, other stiff light material may be employed. To this back 1 is secured the back of the cover 3, the opposite sides of which are 60 flexibly attached to the side boards 4 and 5. To the back 1 may be also attached a ring or loop 6 to facilitate the withdrawal of the album from a cabinet.

Secured to said back 1 in the grooves 2 of 65 the inner side thereof are a series of record holding units 7, each unit having its rear edge snugly fitted into a groove respectively, and each having a series of oblong eyelets 8 adjacent said rear edge of the same. 70

Also secured to the back 1 by screws 9 are a series of longitudinally curved locking or retaining bars 10, the said screws entering the inner side of said back on the ribs 11 between said grooves 2 and said bars 10 being 75 separated from each other longitudinally of said back by distances corresponding to the distances between the eyelets 8 in said record holding units 7. Preferably said retaining bars 10 are rectangular in transverse 80 cross-section and comparatively snugly fit into the oblong eyelets 8. The thickness of the inner edge of each unit 7 is substantially the same as the width of the groove 2 with which it is adapted to be fitted, so that 85 when each unit is placed in position in its respective groove and the locking or retaining bars 10 are inserted through said eyelets 8 and is secured to the back 1 by the said screws 9, the inner edge of said units will be 90 firmly and rigidly secured to said back 1. Said locking bars 10 are preferably longitudinally curved to conform to the curvature of the inner side of the back 1.

Each record containing or holding unit 7 95 consists of a plurality of envelops and in the drawings of this application I have shown each unit as comprising two envelops 12 and 13, although, if desired, more than two envelops may be combined to form a unit. 100 These envelops are securely fastened together adjacent their rear edge by said eyelets 8. Each envelop preferably consists of a single sheet of stiff paper or other flexible material folded to form an envelop closed on 105 three sides and open at the top. In the

drawings is plainly illustrated the manner in which each sheet of paper is folded to make an envelop. Beginning at the vertical edge 14, the sheet extends rearwardly to the rear edge 15 of the envelop to form a flap 16, is then folded at said edge 15 and extends to the front edge 17 to form the front side 18, from which edge 17, said sheet is folded rearwardly to the vertical line 19 lying with 5 in the flap 16, to form the rear side 20 of the envelop. Along the line 19, said sheet is again folded, and brought forwardly, and terminates in an edge 21 substantially parallel to the first mentioned edge 14 to form a flap 22. The forward edge of the flap 16 is glued or cemented to the rear side 20 of the envelop and the front side of the flap 22 is glued or cemented to the inner side of the front 18 of the envelop.

10 The lower edge 23 of each envelop is provided with a flap 24 which is folded upwardly and is glued or cemented to the back of the rear side 20 of the envelop.

By the above construction, it will be apparent that between the edges 14 and 19 there is a double thickness of the material of the envelop to stiffen the envelop and similarly between the edges 19 and 21 there is another double thickness of the said material for the same purpose. With the rear edge of each unit snugly fitted within the grooves 2 of the back 1 and with each envelop or container provided with the stiffened portions above described as lying between the edges 14, 19, and 21, the whole construction of the envelop is very materially stiffened, and made durable, and the liability of breaking or tearing an envelop out of the cover is greatly reduced. The 25 providing of the envelop with the fold along the edge 19 also prevents the record contained between the front and rear sides 18 and 20 respectively of the envelop from slipping any nearer or closer to the back than the edge 19. It is to be understood that this 30 feature of the invention is not dependent upon the particular side of the album to which the envelops are attached, but the folded portion 19 of the envelop is located adjacent that edge by which the envelop is secured to the album and operates to maintain the records in the holder away from the securing edge of the envelops, it being immaterial whether they are secured at the back or at the side of the album in so far as 35 this feature of the invention is concerned, so long as the records are kept away from the hinging portion of the envelops forming the leaves of the album. Inasmuch as the 40 units are flexible between the edge 19 and their point of attachment to the retaining or locking bars 10, this construction reduces the liability of the record being broken as the lids of the album are turned. Moreover, the fold along the edge 19 prevents

the records from slipping rearwardly and becoming wedged between the converging front and rear sides of the envelop, which wedging action would have a tendency to unduly weaken the flexible portion between 70 the edge 19 and the eyelets, and would tend to separate the front and rear portions of the envelop by tearing them from their eyelets 8, and from the back 1.

Secured to the ends of the back 1 and 75 overlying the grooves 2 therein, are end plates 25—25, each secured to the back 1 by screws 26 extending into the back longitudinally of the ribs 11 formed between the grooves 2 on the inner side of the back 1. 80

These plates are adapted to stiffen the back, and to prevent injury or breaking of the ribs 11 as the record album, filled with records, is drawn out of and replaced into a record cabinet, and serves to give the top 85 and bottom of the book a very neat, attractive and strong appearance.

By virtue of the above construction, a very strong, neat and durable record album is easily constructed, the same being provided with record containing units which are readily inserted in place, and firmly united to the back, and in which, when a record containing envelop becomes worn or broken or torn, a new one may be inserted, 95 to replace the broken one, without making it necessary to replace or change any other unit than the one of which said envelop is a part.

Although I have described but one embodiment of my invention, I do not wish to be construed as being limited to the exact details of construction, inasmuch as various changes may be made without departing from the spirit and scope of this invention 105 as defined in the appended claims.

What I claim and desire to secure by Letters Patent is:

1. In an album for holding talking machine records, the combination of a back 110 having a series of longitudinal grooves in the inner side thereof, a cover secured to said back, a series of record holding units each unit snugly fitting into a groove in said back respectively and having a series 115 of eyelets adjacent the rear edge thereof for holding said units together, and a series of retaining bars secured to the said inner side of said back and overlying said grooves and spaced from each other to correspond to the 120 spaces between said eyelets in said units.

2. In an album for holding talking machine records, the combination of a holder and an envelop retained therein at one edge, consisting of a single folded sheet of suitable 125 material provided with a doubled portion adjacent but spaced from and parallel to said edge, forming means to retain a record in the envelop away from said retaining edge. 130

3. In an album for holding talking machine records, the combination of a back provided with means to retain record holding envelopes therein with a plurality of envelopes provided with integral hinging means coöperating with said retaining means on the back to hinge the envelopes in

the album, said envelopes provided with means to retain the records forwardly away from the hinge.

In witness whereof, I have hereunto set my hand, this third day of November, 1915.

10

FARRON S. BETTS.
